2,474,403

ARC LAMP AND ITS LOW-TENSION IGNITION

David Reichinstein, Zurich, Switzerland

Application March 18, 1944, Serial No. 527,053
In Switzerland October 15, 1942Section 1, Public Law 690, August 8, 1946
Patent expires March 8, 1963

3 Claims. (Cl. 315—278)

1

The present invention refers to an arc lamp equipped with electrodes of high melting point (i. e. not less than 2000° C.) arranged in fixed position in relation to each other in a closed gas-filled space, the lamp being of such a design that in service the radiation of light proceeds from the incandescent electrodes.

With a view to lowering the ignition tension of such lamps it has already been proposed to insert auxiliary magnesium electrodes supplying the pre-ionization for igniting the main electrodes.

It is further known that by means of an incandescent wire an auxiliary arc can be initiated at lower voltage, subsequently jumping over on to the main electrodes.

This auxiliary arc, however, involves various difficulties which have hitherto practically prevented a regular reliable service. If, for instance, there is only a small interval between the auxiliary electrodes and the main electrodes, the auxiliary electrodes will fail to function inasmuch as their arc will be extinguished as soon as the main electrodes begin to glow, and the auxiliary wire melt through. If, on the other hand, the auxiliary electrodes are too far distant from the points of the main electrodes ignition will be unreliable. (See for reference Ediswan-Pointolite-Lamp: Skaupy "Elektrotechnische Zeitschrift 1927" vol. 48, page 1798).

The present invention refers to two new means of utilizing the Richardson effect for lowering the ignition tension. The first by means of a heating wire wound round the main electrodes—which wire, however, is completely isolated from the main electrodes, and consequently does not produce an auxiliary arc, merely serving to heat the main electrodes, thus lowering their ignition voltage.

In the second form of the invention an auxiliary arc does form, but this auxiliary arc does not strike off the heated electrode, but off the points provided there which have the characteristics of lightning conductors; by means of the device more particularly described below and based on the principle of the competition between two arcs, this auxiliary arc jumps over on to the two main electrodes and is automatically extinguished.

The following description deals, with the assistance of the drawings in Figs. 1-4, with two constructional examples of the present invention, whilst Fig. 5 represents the system of connections making it possible to ignite the lamp at low voltage.

2

In the arc lamp of Figure 1, the lead-in wires 2, 3, are at the same time carriers of the electrodes 4, 5, and are melted into the closed glass bulb 1 containing a gas which is inactive in relation to the other materials of which the lamp is made up. Furthermore, there are further lead-in wires and carrier parts 7, 8 for the electrode heating wire 6, melted into the glass bulb 1. This heating wire 6 serving as auxiliary heating means for the electrodes is wound round the electrodes 4, 5. As may be seen from Fig. 1, the lead-in wires 2, 3 for the electrodes 4, 5, are independent from the lead-in wires 7, 8 for the heating wire 6. The electrodes are made of metals with a high melting point, of carbon, graphite (first class conductor) or metallic oxides or silicates (second class conductor). The ignition of the lamp is effected by putting under voltage the lead-in wires 2, 3 for the electrodes 4, 5, and the lead-in wires 7, 8 for the heating wire 6. The heating wire pre-heats the main electrodes, increases their electron emission and lowers their ignition tension, so that shortly thereafter the ignition of the arc between the main electrodes takes place, whereupon the heating wire 6 can be disconnected.

Figures 2 to 4 show an arc lamp provided with auxiliary heating means adapted to generate an arc with one of the two main electrodes, which arc then jumps over to the two main electrodes, simultaneously and automatically discontinuing the operation of the auxiliary heating means.

In the glass bulb 9 are the two main electrodes 10, 11 melted on to the lead-in wires 16, 17. The heated auxiliary electrode 14 includes, however, several points 15 which have the characteristics of lightning conductors, the auxiliary arc striking off these points and not off the incandescent electrode 14.

40 In order to ensure that the shortest gap shall not exist between any part of the heating wire and the main electrodes, but between the points of these latter and the lightning conductors the nearest portion of the auxiliary electrode 14 extends transversely to the projections 12, 13 of main electrodes 10, 11, and the lightning conductors 15 are supported by it and extend therefrom towards the projections 12, 13 of the main electrodes 10, 11.

45 Lastly, as regards the shape of the main electrodes, experience has shown that the most suitable shape is evolved by making use of the principle of the Jablotchkoff candle, namely in providing the top of the electrodes with a projection 55 12, 13—say, for example, 1 cm. in length—the

electrodes standing at a small angle in relation to each other (Fig. 4). As to the lamp itself, the most suitable shape will be that of a sphere, with cylinder set upon it pointing upwards; in this cylinder the metallic dust is condensed. Jablotchkoff candle is a device which is well known in the art and which is described, for example, on page 788, volume 2 of the Century Dictionary and Cyclopedias, 1911 edition.

The system of connections for bringing about 10 the ignition of these lamps is shown in Fig. 5.

AB is the public alternating current supply network of, say, 220 volts. To this network is connected the primary coil 19 of the transformer with the connecting terminals 25, 26. Of the two secondary coils 20 and 21, connected together by means of the connection 23, the secondary coil 21 has been designed so that it can also be used for the working of the incandescent electrode 38. The connection of the terminal 22 of the secondary coil with the terminal 26 of the primary coil is intended to be a symbolical representation of the series connection of both coils. 35 is an ammeter, 27, 28, 29, 30 are switches, 31—a push button.

32, 33 and 34 are impedances. By closing 27, 23 and 29 the transformer is connected with the network, whilst the main electrodes 36, 37 receive voltage from the terminals 18 and 24.

This voltage which in the practical case under consideration amounts to approximately 640 volts is, however, not sufficient to bring about the striking of the arc of a lamp whose inert gas, at a pressure of approximately 550 mm. Hg, contains a high percentage of argon. Under these conditions, in order to bring about the striking of an arc without having recourse to an auxiliary electrode, approximately 2000 volts would be required.

However, by causing the auxiliary electrode 38 (incandescent electrode) to glow for one moment with switch 30 closed, there arises immediately between its points and the main electrode 36 an arc which in a short time causes this main electrode to become incandescent, whereupon the switch 30 is opened, the arc jumps over on to the other main electrode 37, and, as soon as the latter becomes incandescent, the arc of the auxiliary electrode is automatically extinguished. In case the distance between the auxiliary electrode and the main electrodes should be somewhat greater, the impedance 34 would not be required. Practice, however, has shown—and this is the essential part of the present invention—that working reliability can only be secured by mounting the auxiliary electrode very close to the main electrodes so that the auxiliary arc shall never fail to strike, whilst the putting in circuit of the impedance 34, brought about by opening the switch 30, causes the arc to jump over on to the second main electrode and the auxiliary arc to become extinguished.

In the practical case considered here the im-

pedance 32 amounted to approximately 500 ohms, and the impedance 34 to approximately 900 ohms. As to the switches, there is no necessity to work each of them separately; on the contrary, the circuits may be closed and opened in proper sequence by means of a drum switch.

I claim:

1. In an arc light radiating lamp comprising two main electrodes, a loop-shaped auxiliary electrode mounted in said lamp transversely and close to said main electrodes to generate an auxiliary arc between itself and one of said main electrodes, a single source of alternating current, a transformer having a single primary coil connected with said source, and a secondary coil consisting of two partial secondary non-uniform coils interconnected in series, means connecting the entire voltage of said coils of the transformer with said main electrodes, an impedance, means electrically connecting said impedance in series with said auxiliary electrode and the smaller of the two partial secondary coils, and a switch connected in parallel with said impedance, whereby the closing of said switch short-circuits said impedance.

2. In an arc lamp comprising an envelope filled with an inert gas, two main electrodes within said envelope, an auxiliary incandescent electrode mounted within said envelope close to said electrodes and adapted to generate an auxiliary arc between itself and one of said electrodes, said main electrodes having the form of a Jablotchkoff candle, said auxiliary electrode comprising a portion extending transversely to the projecting portions of said main electrodes, said auxiliary electrode further comprising pointed portions in the nature of lightning conductors supported by said transverse portion and extending therefrom towards said projecting portions and leads through said envelope to the respective electrodes.

3. In an arc lamp according to claim 2, said projecting portions extending at a small angle in relation to each other.
